US0D1030039S

(12) **United States Design Patent** (10) **Patent No.:** **US D1,030,039 S**
(45) **Date of Patent:** **** Jun. 4, 2024**

(54) **IRRIGATOR**

(71) Applicant: **Thumbs Up Innovations Technology Co., Ltd.**, Guangdong (CN)

(72) Inventors: **Zihui Yang**, Guangdong (CN); **Yuqiang Zhao**, Guangdong (CN); **Yubin Li**, Guangdong (CN); **Xiu Zou**, Guangdong (CN); **Zhidong Wang**, Guangdong (CN); **Jiacheng Huang**, Guangdong (CN); **Lilin Xu**, Guangdong (CN); **Yuanhua Sun**, Guangdong (CN)

(73) Assignee: **Thumbs Up Innovations Technology Co., Ltd.**, Guangdong (CN)

(**) Term: **15 Years**

(21) Appl. No.: **29/800,449**

(22) Filed: **Jul. 21, 2021**

(51) LOC (14) Cl. **24-02**

(52) U.S. Cl.

USPC **D24/111**

(58) **Field of Classification Search**

USPC D24/108, 111-115, 117, 121, 152, 156, D24/176; D4/101, 102, 110, 111, 138
CPC A61C 17/02; A61C 17/028; A61C 1/0015; A61C 1/0061; A61C 15/041; A61C 15/047; A61M 2210/0625; A61M 3/0216; A61M 3/025

(57) **CLAIM**

The ornamental design for an irrigator, as shown and described.

DESCRIPTION

FIG. 1 is a front, right, and top perspective view of an irrigator, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising an on-off switch.

(Continued)

The dot-dash broken lines in the drawings denote the boundaries of the enlarged detail views and form no part of the claimed design.

1 Claim, 9 Drawing Sheets
